UNITED STATES PATENT OFFICE.

GEOEGE LABRIE, OF METHUEN, MASSACHUSETTS.

ROLLER-LATCH.

1,253,393.

Specification of Letters Patent. Patented Jan. 15, 1918.

Application filed July 12, 1917. Serial No. 180,211.

To all whom it may concern:

Be it known that I, GEORGE LABRIE, citizen of Canada, residing at 69 Howe street, Methuen, in the county of Essex and State of Massachusetts, have invented certain new and useful Improvements in Roller-Latches, of which the following is a specification.

This invention relates to what may be called roller latches. It is to be used in connection with a window or door to hold the window or door firmly in place, but in such a manner that it can be displaced by the exercise of necessary amount of force.

It is particularly useful for fire exits as it may be so adjusted that it will not yield except to a comparatively great pressure such as might be exercised by a crowd of people pressing against it. It includes a spring pressed roller which is so mounted that the roller projects a greater or less distance from the edge of the door and its particular features are the fact that the distance of this projection can be readily adjusted, without removing the mechanism, with a common tool, such as a screw driver, and that the tension can be increased or decreased in the same manner. It is also so arranged that when the springs wear out, they can be easily replaced, or a heavier or lighter spring can be easily substituted. It is also preferably made of cast metal.

In the drawings, Figure 1 is a plan view partly in section showing the location of the parts with reference to a door and its casing. Fig. 2 is an elevation partly in section of the casing with roller latch attached. Fig. 3 is a face view as from the right of Fig. 2. Fig. 4 is a plan view, partly in section, of a modification. Fig. 5 is a plan view partly in section, showing the door closed.

A is a door at the edge of which is a groove 10 preferably reinforced by a door plate 11.

B is a casing in which is a suitable recess to receive a plate C which may be attached by means of screws such as 8.

From the back of casing plate C project legs such as 20 and 21. These are shown in Fig. 2 as integral with the casing plate, and in Fig. 4 at 50 as fastened thereto.

Plate C has a long narrow vertical slot 19 which continues into each leg at 25 and farther at 24 as a spring recess and still farther as threaded extension 23.

F is a roller carrier which has at each end, bearings 30 for a shaft 31 upon which is rev- 55 olubly mounted a roller 32.

At each end of roller carrier F is a screw recess 33 with a screw hole 34 through the bottom. Into this recess 33 and through screw hole 34 passes a headed screw 26, the 60 threaded end of which fits into the threaded extension 23 of the slot.

Around each screw such as 26, resting in the leg slot and bearing against the leg and the roller carrier, is a compression spring 27. 65

These springs 27 tend to force the roller carrier and roller outward to the limit determined by the position of the heads of screws 26.

By turning screws 26, the roller carrier 70 may be forced inward against springs 27 or allowed to project outward as desired.

By such adjustment, the distance which roller 32 projects into the path of the edge of door A, may be regulated so that any 75 variations in the distance between the door and casing may be compensated for.

In addition to permitting the device to be attached and adjusted where there is a different distance between the door and the 80 casing, my construction with the adjustable guide screws and springs, together with a groove in the door of sufficient depth, permits me to regulate the amount of force required to open the door. 85

I prefer to use a door plate 11 which slopes at 12 from the casing on the inside as shown in Figs. 1 and 5, the door being cut away to fit, so that the door will readily close. 90

The force required to open the door depends upon whether or not the roller 32 projects well out as shown by the full lines in Fig. 5, so that in attempting to open it, the edge 13 of the door slot will strike it 95 nearly opposite its axis or at outer edge as shown by the dotted lines. It is evident that when this edge strikes near the center or axis, much more force will be required to force inward the roller and carrier against 100 the springs than where it barely touches the outer edge of the roller.

As there is nothing on the door except the door plate, my device is adapted for light weight doors which are to be held lightly 105 from being pushed open, but is equally

adaptable for fire escape doors where it is desired that a great deal of force should be used in order to open them.

It is also clear that by removing the screws 5 26, heavier or lighter removable springs such as 27, can be put in position according to the purpose for which the door is intended.

In Fig. 4 is shown a construction wherein the casing plate H is flat, as, for instance, 10 if it is made of sheet metal, and has fastened to its back by rivets 51 the U shaped legs 50. The space between the branches of each leg 50, as shown at 52, forms an extension of casing plate slot 53, and the end of each leg 15 50 is threaded at 54 to receive the end of screw 26. The roller carrier F is the same as in the first described construction.

There is nothing on my door or casing which can catch on the clothing as my roller 20 and carrier are preferably of smooth metal and the screw heads which are preferably slotted are sunk down out of the way.

I claim:

1. In a roller-latch, a plate having legs at 25 the back and a narrow slot which extends into the legs, in combination with a roller

carrier slidable into and out of the slot and having screw holes, a roller carried thereby, headed screws which pass through the screw holes and the slots into the legs, and compression springs each of which encircles a screw between a leg and the roller carrier. 30

2. In a roller latch, the combination of a roller carrier having recesses and screw holes at each end, a roller carried thereby, 35 and a plate having a slot to receive the roller carrier, with legs fixed to the back of the plate having slots to receive the roller carrier and threaded extensions, headed screws which pass through the recesses and screw 40 holes in the roller carrier and the slots in the plate and legs into their threaded extensions, and removable compression springs which encircle the screws and rest in the leg slots and bear against the roller carrier. 45

In testimony whereof I affix my signature.

GEORGE X LABRIE.
